US00D373711S

United States Patent

[19]

Harrison

[11] Patent Number: Des. 373,711

[45] Date of Patent: **Sep. 17, 1996

[54] **HANDLE FOR FORKS, SPOONS AND TOOTHBRUSH**

D. 294,200 2/1988 Zucker D4/107
D. 296,617 7/1988 Zucker D4/107

[75] Inventor: **Susan Harrison**, Wichita Falls, Tex.

Primary Examiner—Nelson C. Holtje

Assistant Examiner—Caron D. Veynar

Attorney, Agent, or Firm—Cesari and McKenna

[73] Assignee: **Zooth, Inc.**, Wichita Falls, Tex.

[57] CLAIM

[**] Term: **14 Years**

[21] Appl. No.: **40,824**

The ornamental design for a handle for forks, spoons and toothbrushes, as shown and described.

[22] Filed: **Jun. 27, 1995**

DESCRIPTION

[63] Continuation-in-part of Ser. No. 14,501, Oct. 22, 1993, Pat. No. Des. 366,603, and a continuation-in-part of Ser. No. 14,528, Oct. 22, 1993, Pat. No. Des. 364,077, and a continuation-in-part of Ser. No. 14,496, Oct. 22, 1993, Pat. No. Des. 363,651, and a continuation-in-part of Ser. No. 14,500, Oct. 22, 1993, Pat. No. Des. 365,503, which is a continuation-in-part of Ser. No. 3,463, Jan. 12, 1993, Pat. No. 5,269,420.

[52] U.S. Cl. **D7/654; D7/401.2**

FIG. 1 is a perspective view of a handle for forks, spoons and toothbrushes showing my new design;

[58] Field of Search D7/651, 654, 689, D7/393, 395, 401.2; D4/107, 124; D8/107; 30/322, 324; 15/167.1, 167.2, 143.1; 206/15.2, 15.3, 63.5, 349, 361, 362.1-362.4, 457

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing spoon bowl in FIGS. 1-5 and 7 are environmental only and forms no part of the claimed design.
